(57) **CLAIM**

The ornamental design for a modular bed base, as shown and described.

DESCRIPTION

FIG. 1 is a left view of a modular bed base showing my new design;

FIG. 2 is a right view thereof;

FIG. 3 is a front view thereof;

FIG. 4 is a rear view thereof; and

FIG. 5 is a top plan view thereof.

FIG. 6 is a bottom plan view thereof; and,

FIG. 7 is a perspective view thereof; the broken lines showing the whole bed base are for environmental purposes only and form no part of the claimed design.

The modular bed base is shown in broken lines for illustrative purposes only, and forms no part of the claimed design.
